HYDRAULIC OPERATING MECHANISM FOR
WELL PUMPSHerbert Harvey, Los Angeles, Calif., assignor to
Leo M. Harvey, Los Angeles, Calif.

Application September 10, 1946, Serial No. 695,912

13 Claims. (Cl. 60—52)

1

This invention has to do with a pump operating mechanism and is more specifically concerned with a mechanism of a type that can be used to advantage to operate a well pump, as for instance, an oil well pump, it being a general object of the present invention to provide a practical, dependable, effective mechanism of this general character.

The operating mechanism of the present invention can be used to advantage in various situations. However, it is particularly useful for operating a well pump or the like and can be used to great advantage in operating an oil well pump where it is desired to gain a long stroke of the sucker rod which extends into the well to operate the pump. It is generally recognized that the ordinary type of mechanical well pump commonly employed is limited in use, since in deep wells the string of sucker rods becomes so long as to absorb the greater part of the motion imparted to its upper end and, in practice, it has been difficult or impractical to move the upper end of the string of sucker rods through a long stroke such as a deep well requires.

It is a general object of the present invention to provide a pump operating mechanism which utilizes fluid pressure as an operating medium and is such that it can be readily constructed in a manner to impart a very long stroke to a string of sucker rods.

It is an object of the present invention to provide a practical and simple operating mechanism of the general character referred to which involves a constantly operating pressure generator or pump and a high pressure supply means or accumulator which is related to the pump to supply liquid thereto during the up or work stroke of the mechanism. The high pressure supply means of the present mechanism handles the necessary supply of operating liquid as the mechanism is delivering liquid to the jack cylinder to move the sucker rods and it carries a cushion of air under an initial pressure which is increased or supplemented by the delivery of liquid during the period that the jack is lowering the string of sucker rods.

It is a general object of the present invention to provide an operating mechanism of the general character hereinabove referred to which involves a jack mechanism or lift cylinder, an accumulator, and a pumping unit so combined and related through suitable connections and controls as to enable the pump unit to operate continuously and under a substantially constant load while liquid under pressure and in sub-

stantial volume is alternately delivered to the jack and the accumulator. The liquid delivered to the jack works or is utilized to lift the string of sucker rods whereas the liquid delivered to the accumulator is utilized to develop pressure which acts to feed liquid to the pump when it is acting to deliver liquid to the jack.

Another object of the present invention is to provide an improved, simplified, main or working valve which combines in a single compact and practical unit the various essential flow controls required for the handling of liquid to and from the pump unit.

Another object of the present invention is to provide an improved, simple, and effective control means responsive to the action of the jack and controlling the operation of an operating means for the main or working valve and which is characterized by a pilot valve involving a simple, dependable hydraulic latch which insures dependable operation of the mechanism.

A further object of the present invention is to provide a simple, practical, efficient means which serves to supply air to the mechanism so that air that leaks or is lost from the mechanism in the course of operation is replenished, eliminating the danger of the mechanism failing to function properly for want of the proper amount of air in the system.

Another object of the present invention is to provide a simple practical dependable means for supplying liquid to the apparatus to serve as a feed or make-up for liquid that may leak or be lost in the course of operation. The apparatus is not only adequately supplied with make-up feed but is such that any excess of liquid is effectively removed during the normal course of operation, eliminating danger of improper operation that might result if the apparatus were overloaded with liquid.

The various objects and features of my invention will be fully understood from the following detailed description of a typical preferred form and application of the invention, throughout which description reference is made to the accompanying drawings, in which:

Fig. 1 is a side elevation of a typical preferred form of the invention, showing the general relationship of the essential elements. Fig. 2 is a plan view of the machine shown in Fig. 1, being a view taken as indicated by line 2—2 on Fig. 1. Fig. 3 is an end view of the structure taken as indicated by line 3—3 on Fig. 1. Fig. 4 is a diagrammatic view illustrating the general system involved in the apparatus. Fig. 5 is an enlarged

detailed sectional view of the main or working valve, being a view taken as indicated by line 5—5 on Fig. 2, and showing the valve positioned to admit liquid from the pump to the jack so the jack is operated upwardly. Fig. 6 is a fragmentary view of a part of the structure shown in Fig. 5, being a view taken as indicated by line 6—6 on Fig. 5. Fig. 7 is a view similar to Fig. 5, showing the parts in the opposite or reversed position so that flow from the pump is communicated to the accumulator being a view taken as indicated by line 7—7 on Fig. 5. Fig. 8 is a fragmentary view of a part of the structure shown in Fig. 7, being a view taken as indicated by line 8—8 on Fig. 7. Fig. 9 is a detailed transverse sectional view of the structure shown in Figs. 5 and 7, being a view taken as indicated by line 9—9 on Fig. 5. Fig. 10 is a transverse sectional view taken as indicated by line 10—10 on Fig. 5. Fig. 11 is a longitudinal detailed sectional view of the pilot valve involved in the control means, showing the valve positioned as it is when the jack is operating upwardly. Fig. 12 is a view similar to Fig. 11, showing the parts positioned as they are when the jack is moving downwardly. Fig. 13 is a transverse sectional view taken as indicated by line 13—13 on Fig. 11. Fig. 14 is a transverse sectional view taken as indicated by line 14—14 on Fig. 11. Fig. 15 is a detailed transverse sectional view taken as indicated by line 15—15 on Fig. 12. Fig. 16 is an enlarged sectional view of a portion of the operating means showing the port construction involved in such means. Fig. 17 is an enlarged view taken as indicated by line 17—17 on Fig. 16, and Fig. 18 is a view showing the liquid make-up pump with the inlet thereto broken away to show the manner in which air is admitted to the apparatus.

The structure provided by the present invention involves, generally, a jack A that may be arranged and connected to operate a string of sucker rods or the like, a fluid pressure generating means B involving, essentially, a constantly driven centrifugal pump, a high pressure supply means or accumulator C for the pump of means B, a main or working valve D connected with and between the elements A, B and C, operating means E for the valve D, control means F for the operating means E relating the operating means E to the jack A, a fluid reservoir G carrying a suitable supply of liquid, a reservoir H carrying a supply of air, a liquid make-up or feed means J receiving liquid from the reservoir G and introducing it into the apparatus, an air supply means K delivering air to the reservoir H, and means L serving to intermittently discharge excess liquid from the apparatus.

In accordance with the broader principles of the present invention the various essential elements hereinabove enumerated may vary widely in form, character and arrangement and in any particular adaptation of the invention such details will be governed largely by working conditions that are encountered. In the drawings I have shown a typical form and arrangement of elements and have shown a practical unit wherein in the various elements, except for the jack, are assembled on a frame or skid 10 to form a unit that can be readily moved and in which the parts are effectively supported in proper cooperative relationship.

The jack A may, broadly, be any suitable hydraulic device which lends itself to operation by apparatus such as I am about to describe. In practice it is generally preferred that the jack A be a simple, hydraulic jack of the cylinder and

piston type, in which case it involves a cylinder 11 closed at its upper and lower ends by heads 12 and 13, and a piston 14 operating in the cylinder and carried by a rod 15 extending into the cylinder through one of the heads. In the case of a jack for operating a string of sucker rods or the like the cylinder 11 is vertically arranged over the well. For instance, it may be mounted on a frame or head construction 16 at the top of the well and the rod 15 which carries the piston 14 may be a continuation of the polish rod 17 which may be coupled to and form a continuation of a string of sucker rods operating a suitable pump located in a well and may extend through suitable packing glands or stuffing boxes 18 provided in the head construction 16.

In the typical case illustrated a liquid connection 11 is provided at the lower end portion of the cylinder 11 and serves to handle liquid flowing to and from the cylinder. Fluid or liquid introduced through the connection 11 will act under the piston 14 to force the piston up in the cylinder 11, whereas the weight of the piston, sucker rod and other connected parts serves to move the piston down and displace the liquid during the down stroke.

The fluid pressure generating means involves, primarily, a pump 19, preferably a centrifugal pump and a suitable drive or operating means for the pump. In the case illustrated I have shown a suitably housed internal combustion engine or prime mover 20 for driving the pump 19 and I show a belt drive 21 between the engine shaft 22 and the pump shaft 23.

The high pressure supply means or accumulator C operates to handle a supply of liquid and a body of air which acts as an air cushion, the liquid and air being confined so that the liquid is available to feed the intake of the pump 19 while the air is under pressure and acts on the liquid so that the pump is fed under pressure. The preferred form of accumulator C, as shown in the drawings, involves a primary vessel or surge tank 24 and a secondary vessel or air tank 25. The upper end portions of the tanks 24 and 25 are connected by a top connection or duct 26 while a supply pipe 27 connects with the bottom of the surge tank and extends to the main valve D, being connected to the valve D through a suitable control valve 28. In practice the tanks 24 and 25 may vary widely in form, shape and arrangement and therefore the particular arrangement illustrated in the drawings is considered merely as typical and for purpose of example.

The surge tank is shown as a horizontally disposed cylindrical tank closed at its ends and it serves, primarily, to handle liquid discharged from the jack A as the piston of the jack moves down, and to make such liquid available to feed or supply the pump 19 as the piston of the jack moves up. The fluid connection 27 and the valve D handle this flow of liquid to and from the tank 24 and it will be understood that the tank is made sufficiently large to adequately handle the necessary supply of liquid. The surge tank, in addition to handling liquid, as above described, accommodates a body of air above the liquid which air is in communication through the top connection 26 with that carried in tank 25.

The air tank 25 is provided primarily as a carrier for air under pressure. However, during normal operation of the apparatus a small quantity liquid will gradually accumulate in the bottom of tank 25 by reason of having reached

the tank 25 through connection 26. I provide for transfer of excess liquid from tank 24 to tank 25 by providing a down spout 29 on the end of connection 26 in tank 24. As liquid enters tank 24 the pressure of air above the liquid in tank 24 and in tank 25 increases until the liquid covers the lower end of the down spout 29, whereupon a further rise in level of liquid in tank 24 causes an increased pressure to develop on the air in tank 24, with the result that liquid is forced up throughout the down spout and if there is an excess of liquid present it will be forced out through the connection 26 and into tank 25 to accumulate in the bottom of tank 25.

The means L is provided for discharging excess liquid from the bottom of tank 25. The means L may be any suitable form of liquid discharge control. For instance as shown in the drawings, a drain pipe 30 may extend from the bottom of tank 25 to the reservoir G and may carry a diaphragm control valve 31. The diaphragm control valve 31 may be under control of a float valve 32 through a suitable connection 33 and the float valve 32 may be so located that when a predetermined liquid level develops in tank 25 valve 32 operates causing operation of valve 31 so that liquid is drained out of tank 25 into reservoir G.

The main or working valve D is shown in detail in Figs. 5 to 10, inclusive. In its preferred form this valve is of the piston type or is a slide valve and as shown in the drawings it involves, generally, a cylinder 34 which is preferably vertically disposed and two spaced valve heads 35 and 36 carried on a stem 37 and operating in the cylinder 34. In the particular case illustrated the cylinder 34 is vertically disposed and it is provided with longitudinally spaced ports with which the valve heads 35 and 36 cooperate. The cylinder has a lower end port 38 which communicates with a manifold 39 on the exterior of the cylinder, which manifold in turn is connected with the intake line 40 extending to the pump 19. An upper end port 41 is provided in the cylinder 34 and is also in communication with the manifold 39 to be in communication with the pump inlet line 40. Between the upper and lower ports 41 and 38 the cylinder has a port 42 communicating with a manifold 43 connected with the pipe 27 that extends to the lower end of the surge tank 24. Further, between ports 41 and 38 and above port 42 there is a port 44 communicating with a manifold 45 which connects to the discharge line 46 from the pump 19. Further, between the ports 41 and 38 and above the port 44 to be between port 44 and port 41 there is a port 47 which communicates with a manifold 48 connected with a line 49 that extends to the connection 11 at the lower end of the jack cylinder 11.

The valve heads 35 and 36 are carried by the stem 37 so that they are spaced apart longitudinally of the cylinder 34 and so that when the valve is in the up position, as shown in Fig. 5, the head 35 separates ports 41 and 47 while head 36 separates ports 42 and 44, ports 44 and 47 being in communication since they occur between the heads. When the valve is in the down position, as shown in Fig. 7 head 35 is located to separate ports 44 and 47 and head 36 is located to separate ports 38 and 42 while ports 42 and 44 are in communication since they occur between the heads.

Through the system of ports and the relationship of the valve heads to the ports above de-

scribed the main control valve is shiftable between what I will term an up position where it connects the suction of the pump 19 with the accumulator through ports 42 and 38 while the discharge from the pump is connected with the jack through ports 44 and 47, and a down position where it connects the discharge of the pump with the accumulator through ports 44 and 42, while the jack is connected with the suction of the pump through ports 41 and 47. During delivery of liquid through the valve D to the jack the piston 14 of the jack is forced upwardly in the cylinder 11 while the intake of the pump is supplied with liquid under the pressure present in the accumulator C. While the piston 14 of the jack is moving down liquid from the cylinder 11 of the jack is delivered to the suction of the pump and the liquid delivered by the pump is supplied to the accumulator where the cushion of air develops the desired pressure. It is to be understood that the air in the accumulator can be initially put under a suitable pressure so that the system just referred to is, in effect, a loaded or charged system operating under a high pressure. For example, in practice it may be desirable to put an initial pressure on the air in the accumulator sufficient so that the liquid in the system is under enough pressure by reason of the air in the accumulator to effect full operation of the jack proper, and the string of sucker rods connected thereto, plus about one half the load of the column of fluid being handled by the pump attached to the sucker rod.

The operating means E provided to work or operate the main valve between the two positions just described may be any suitable mechanism or device that will effect the necessary relative movement between the valve cylinder and the valve heads. In practice I prefer to employ a simple cylinder and piston mechanism for this purpose, in which case the rod 31 which connects the valve heads 35 and 36 may be extended out of the cylinder through one of its ends or heads through a suitable packing means 50 to a point where it can be connected to a rod 51 carrying a piston 52 operating in a cylinder 53 located above and in alignment with the cylinder 34. In the particular construction illustrated the cylinder 53 is mounted on the head 55 of cylinder 34 through which the stem 37 extends. A cylindrical cage 56 extends from the head 55 to support the cylinder 53. The cage 56 has side openings 57, and a coupler 58 is provided to connect stem 37 with stem 51. The coupler 58 has projecting arms 59 which extend laterally from the stem 51 to cooperate with stops 59a provided in the cage 56 as a stop means for the combined mechanism formed by the connected valve D and means E. The stops may be rings carried in the cage 56.

The cylinder 53 of means E is provided at each end with a main port 60 and each port 60 communicates with a manifold 61 at the exterior of the cylinder. Adjacent each port 60 and spaced therefrom toward the end of the cylinder 53 there is a cushioning port 62 which is a small port which allows for gradual escape of fluid trapped when the piston 52 passes port 60. A supply line 63 handling operating fluid to and from the control means F connects to the manifold of the upper port 60 while a supply line 64 handling operating fluid to and from the means F connects to the manifold of the lower port 60.

The control means F includes, primarily, a device that I will refer to as a pilot valve and

suitable connections between the pilot valve and the other elements of the device. The pilot valve is a piston valve involving, generally, an elongate cylindrical body 65 and a stem 66 extending through the body and carrying valve heads 67 and 68 which cooperate with ports in the valve body. Operating fluid is maintained under pressure in the middle portion of the valve body being delivered to the valve body through a supply pipe 69 connected to one side of the pump 19, preferably the discharge side.

Liquid is admitted to the valve body from the line 69 through a central inlet port 70. Outlet ports 71 and 72 are provided in the valve body in either direction from the port 70, the port 71 being connected with a manifold 73 to which line 63 is connected and the port 72 being connected with a manifold 74 to which line 64 is connected. A port 75 longitudinally spaced from port 71 connects manifold 73 with the interior of the valve body and an exhaust port 76 located between ports 71 and 75 connects the interior of the body with a drain line 77. A port 78 longitudinally removed from port 72 connects manifold 74 with the interior of the body and a port 79 located between ports 72 and 78 connects the interior of the body with a drain line 80. The drain lines 77 and 80 are under control of valves 71^a and 80^a respectively and they connect together or to a drainage system which extends to the liquid reservoir G.

The valve heads 67 and 68 are carried on the stem 66 so that when the stem is to the right, as shown in Fig. 11, the head 67 closes port 71 cutting off communication between ports 70 and 71 but allowing free communication between ports 75 and 76, with the result that liquid is free to drain from line 63 through the valve to the drain line 77 where the rate of flow may be controlled by the valve 71^a. At the same time head 68 closes port 79 so there is no drainage into line 80 but rather port 70 is in communication with port 72 so that fluid under pressure from line 69 passes to and through line 64. With liquid allowed to drain from line 63 and being supplied under pressure to line 64 piston 53 of means E is subjected to pressure which causes it to move up until it reaches the upper end of cylinder 53. The speed at which the piston travels up is controlled by the valve 71^a. When the stem 66 is at the left, as shown in Fig. 12, the general relationship just described is reversed and line 64 is connected with drain 80 while line 63 is connected with the supply line 69 with the result that pressure is applied above piston 52 causing it to move down until it reaches the lower end of cylinder 53. The speed at which the piston travels down is controlled by the valve 80^a.

The control means F further includes parts and connections to effect shifting of the stem 66 between the two positions just described. An extension 85 of the stem 66 forms a ram which enters and operates in a cylinder 86 at the left-hand end of the valve body 65 and a line 87 from the suction of pump 19 is connected with cylinder 86. A head 88 on the end of stem 66 operates in the end portion of the valve body 65 so that a catch chamber 89 is formed to catch liquid leaking from cylinder 86 and it forms an end wall in the body opening with which port 75 communicates. A drain line 90 connects the chamber 89 with the drainage system that returns liquid to the reservoir G.

At the other end of the valve body 65 an extension 91 of the stem 66 forms a ram operating

in a cylinder 92 and a line 93 connects cylinder 92 with the upper end portion of the cylinder 11 of the pump jack. A port 95 is provided in the valve body 65 between the cylinder 92 and the port 78 and is connected with the lower end portion of the cylinder of the pump jack by line 96. A valve head 97 on the stem 66 cooperates with port 95 to extend over and cover it when the stem is to the right, as shown in Fig. 11, and to uncover it when the stem is to the left, as shown in Fig. 12. A chamber 100 occurs between the ram 91 and the valve head 97 and a drain line 101 connects with chamber 100 so that any liquid leaking into it is drained into the drainage system which connects with reservoir G.

With the parts and connections just described when the piston 14 of the pump jack is below the point where line 96 connects into cylinder 11, lines 93 and 96 are both under atmospheric pressure, since atmospheric pressure is admitted to cylinder 11 above the piston 14 through vents 110 at the upper end of cylinder 11. When this condition prevails the pressure that is on the pump suction, being the pressure exerted by reason of the pressure maintained or always present in the accumulator, acts on the ram 86 to move the stem 66 to the right, as shown in Fig. 11. When the piston 14 starts to move up in cylinder 11 and after it has passed the point where line 96 connects to cylinder 11, fluid pressure from the discharge side of the pump 19 is admitted through the cylinder of the pump jack to the line 96 but, as shown in Fig. 11, this pressure has no action on the pilot valve since the valve head 97 covers port 95. When the piston 14 is moved to the upper end of the cylinder 11 and has moved past the point where line 93 connects into cylinder 11, the high pressure fluid in cylinder 11 beneath piston 14 is admitted through the line 93 to ram 91. Since this pressure is greater than that on the suction side of the system, which suction pressure is communicated through line 87, the ram 91 causes the stem 66 to be moved to the left and as soon as the valve head 97 uncovers port 95 the pressure admitted through line 96 acts on valve head 97 further urging it to the left and this pressure will remain on the valve head 97 and hold the stem 66 latched to the left until the piston 14 has returned to the lower end of the stroke to uncover the point where line 96 connects into cylinder 11.

In the operation of a system such as I have described there is, in practice, always some leakage of liquid and conditions vary due to change in temperatures, etc. and therefore I provide the means J, which is a fluid make-up or feed pump, to deliver a small quantity of liquid from reservoir G into the system during normal operation thereof. In practice I preferably provide a small, positive pump 115 operated by the prime mover 20, as through a belt drive 116. The pump is supplied with liquid from the reservoir through a supply line 117 and delivers liquid through a suitable check valve 118 and delivery line 119 which line is shown connected into the surge tank of the accumulator.

In practice it is also desirable to maintain a substantially constant quantity of air in the apparatus and since I have provided the means L which serves to periodically empty a quantity of liquid from tank 25 it is desirable to provide the make-up air quickly and in a quantity so that there is not a period when the system is without adequate air. For this purpose I provide the air reservoir H which may be a tank that

will carry a suitable quantity of air and I connect the tank H with the air tank 25 by a line 128 and I provide a suitable pressure regulator 121 in the line 128 so that when the pressure of air in tank 25 drops below a predetermined value the regulator opens and allows air from tank H to flow into tank 25. The means H will ordinarily deliver air into the tank 25 when the pressure is minimum or when the tank 24 has been emptied of liquid a sufficient amount to raise the piston 14 to the top of the cylinder 11.

The means K supplies air to the tank H and it may involve a small air compressor 130 driven by the prime mover of means B as by a belt drive 131. I have shown the air pump 130 connected with the tank H by a line 140 equipped with a pressure regulating valve 141 which determines the pressure allowed to build up in tank H. In practice I supplement the construction just described by a bleeding means which operates to normally bleed a small amount of air into the system. For instance, in Fig. 18 of the drawings I show the inlet portion of the line 117 which admits liquid to the pump 115 provided with a small air inlet opening 151 so that normally as the apparatus operates a small amount of air is drawn in with the liquid passing through line 117. The air inlet opening 151 is proportioned so that it normally admits a minimum requirement of auxiliary air or make-up air into the system and the pump 130 is operated so that it makes up the additional amount of required air plus a small excess which may be allowed to escape by means of the regulator 141. Through this arrangement a very small air pump is all that is required to effectively maintain the proper air supply in the system.

From the foregoing description it will be apparent that the system is initially supplied with a proper amount of liquid and the accumulator is put under pressure, that is, the air in the accumulator is put under the desired or proper pressure. As the mechanism operates the control means F, being coupled with the pump jack by the lines 93 and 96 acts in direct response to the position of the piston 14 of the pump jack in the cylinder 11 so that the pilot valve mechanism of means F reverses as the piston 14 reaches the ends of its stroke. Reversal of the pilot valve of means F effects reversal of the pressure conditions on means E with the result that when the pilot valve reverses means E reverses and in so doing it reverses the valve D. The reversal of valve D or the shifting of valve D between the positions shown in Figs. 5 and 7 changes the direction of operation of the pump jack while allowing the pump 19 of means B to operate constantly and so that as the pump jack moves down the pump D builds up pressure in the accumulator which is used on the following up stroke, at which time it is applied to the intake of the pump 19.

The jack A, and the operating means E are operated by the working pressure from the accumulator means C and the pump B, and the control means F or the pilot valve is operated by the pressures from the jack A. Liquid used to operate the pilot valve is delivered back to the reservoir through a suitable connection or line 150 which connects the top of the jack with the reservoir G. The pressure in the system will vary, for instance, it will be higher as the piston 14 of the jack progresses down, and lower as the piston is going up. Therefore, whenever the pressure in the accumulator becomes through loss

of air, lower than the minimum requirement, then the means H will charge it quickly to the minimum requirement only. The maximum requirement will be attained when the liquid is moved from the jack to the accumulator, whereupon any excess liquid is transferred from tank 24 to tank 25 from which is it dumped into the reservoir G by the means L.

Having described only a typical preferred form and application of my invention, I do not wish to be limited or restricted to the specific details herein set forth, but wish to reserve to myself any variations or modifications that may appear to those skilled in the art, and fall within the scope of the following claims.

Having described my invention, I claim:

1. In combination, a pump having an inlet and an outlet, a jack, means connecting the pump and jack intermittently directing flow from the outlet of the pump to the jack, and a control for said means including a valve, a fluid connection between the valve and jack controlled by the action of the jack and communicating pressure to the valve to operate it in one direction, and a fluid connection between the valve and the inlet of the pump supplying fluid to the valve to operate it in the opposite direction when the first mentioned connection is not supplying pressure to operate the valve.

2. In combination, a pump having an inlet and an outlet, a jack including a cylinder and a piston operating in the cylinder, means connecting the pump and jack intermittently directing flow from the outlet of the pump to the jack, and a control for said means including a valve, a fluid connection between the valve and jack controlled by the action of the piston of the jack and communicating pressure to the valve to operate it, and a fluid connection between the valve and the inlet of the pump supplying fluid to the valve to operate it when the first mentioned connection is not supplying pressure to operate the valve, the first mentioned connection including pressure communicating lines from each end portion of the cylinder to the valve.

3. In combination, a pump having an inlet and an outlet, a jack including a cylinder and a piston operating in the cylinder, means connecting the pump and jack intermittently directing flow from the outlet of the pump to the jack and including a fluid pressure actuated operating means, and a control for said operating means including a pilot valve controlling operating pressure for the operating means, a fluid connection between the valve and jack controlled by the action of the jack and communicating pressure to the valve to operate it, and a fluid connection between the valve and the inlet of the pump supplying fluid to the valve to operate it when the first mentioned connection is not supplying pressure to operate the valve, the first mentioned connection including a pressure communicating line connected to the cylinder and open to pressure from the cylinder only when the piston is at one end of its stroke and connected to the valve so pressure therefrom operates the valve and a pressure communicating line connected to the cylinder to be open to pressure from the cylinder except when the piston is at the other end of its stroke and connected to the valve so pressure therefrom holds the valve operated after it has been operated by pressure from the first mentioned line until the piston reaches the said other end of its stroke.

11

4. In combination, a pump having an inlet and an outlet, a jack including a vertically disposed cylinder and a piston operating in the cylinder, means connecting the pump and jack intermittently directing flow from the outlet of the pump to the jack and including a fluid pressure operating means, and a control for said operating means including a pilot valve controlling operating pressure for the operating means, a fluid connection between the valve and jack controlled by the action of the jack and communicating pressure to the valve to operate it, and a fluid connection between the valve and the inlet of the pump supplying fluid to the valve normally tending to operate it when the first mentioned connection is not supplying pressure to operate the valve, the first mentioned connection including a pressure communicating line connected to the cylinder and open to pressure from the cylinder only when the piston is at the upper end of its stroke and connected to the valve so pressure therefrom operates the valve and a pressure communicating line connected to the cylinder to be open to pressure from the cylinder except when the piston is at the lower end of its stroke and connected to the valve so pressure therefrom holds the valve operated after it has been operated by pressure from the first mentioned line until the piston reaches the said lower end of its stroke.

5. In combination, a pump having an inlet and an outlet, a jack including a cylinder and a piston operating in the cylinder, means connecting the pump and jack intermittently directing flow from the outlet of the pump to the jack and including a fluid pressure actuated operating means, and a control for said operating means including a pilot valve controlling operating pressure for the operating means, a fluid connection between the valve and jack controlled by the action of the jack and communicating pressure to the valve to operate it, and a fluid connection between the valve and the inlet of the pump supplying fluid to the valve to operate it when the first mentioned connection is not supplying pressure to operate the valve, the first mentioned connection including a pressure communicating line connected to the cylinder and open to pressure from the cylinder only when the piston is at one end of its stroke and connected to the valve so pressure therefrom operates the valve and a pressure communicating line connected to the cylinder to be open to pressure from the cylinder except when the piston is at the other end of its stroke and connected to the valve so pressure therefrom holds the valve operated after it has been operated by pressure from the first mentioned line until the piston reaches the said other end of its stroke, the pilot valve including a shiftable valve element and a ram in connection with said element operated by pressure from the first mentioned line and a head connected with the ram and operated by the pressure from the other line.

6. In combination, a pump having an inlet and an outlet, a jack including a cylinder and a piston operating in the cylinder, means connecting the pump and jack intermittently directing flow from the outlet of the pump to the jack and including a fluid pressure actuated operating means, and a control for said operating means including a pilot valve controlling operating pressure for the operating means, a fluid connection between the valve and jack controlled by the action of the jack and communicating pressure

75

12

to the valve to operate it, and a fluid connection between the valve and the inlet of the pump supplying fluid to the valve normally tending to operate it when the first mentioned connection is not supplying pressure to operate the valve, the first mentioned connection including a pressure communicating line connected to the cylinder and open to pressure from the cylinder only when the piston is at one end of its stroke and connected to the valve so pressure therefrom operates the valve and a pressure communicating line connected to the cylinder to be open to pressure from the cylinder except when the piston is at the other end of its stroke and connected to the valve so pressure therefrom holds the valve operated after it has been operated by pressure from the first mentioned line until the piston reaches the said other end of its stroke, the pilot valve including a body with fluid handling ports, and a shiftable element operating in the body having heads controlling the ports, a ram at one end receiving pressure from the pump inlet, a ram at the other end receiving pressure from the first mentioned line and a head receiving pressure from the other line.

7. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack and including a surge tank handling liquid from and delivering it to the pump, an air tank, and a connection between the tanks, and a control for said means including a valve, a fluid connection between the valve and jack controlled by the action of the jack and communicating pressure to the valve to operate it, and a fluid connection between the valve and the inlet of the pump supplying fluid to the valve to operate it when the first mentioned connection is not supplying pressure to operate the valve.

8. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack and including a surge tank handling liquid from and delivering it to the pump, an air tank, a connection between the tanks, and means acting to drain liquid from the air tank upon a predetermined quantity thereof accumulating therein, and a control for the first mentioned means including a pilot valve, a fluid connection between the pilot valve and jack controlled by the action of the jack and communicating pressure to the pilot valve to operate it, and a fluid connection between the pilot valve and the inlet of the pump supplying fluid to the pilot valve to operate it when the first mentioned connection is not supplying pressure to operate the pilot valve.

9. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack and including a surge tank handling liquid from and delivering

13

it to the pump, an air tank, a connection between the tanks, and means acting to drain liquid from the air tank upon a predetermined quantity thereof accumulating therein and a control for the first mentioned means including a pilot valve, a fluid connection between the pilot valve and jack controlled by the action of the jack and communicating pressure to the pilot valve to operate it, a fluid connection between the pilot valve and the inlet of the pump supplying fluid to the pilot valve to operate it when the first mentioned connection is not supplying pressure to operate the pilot valve, and means operating to add air to the accumulator.

10. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack and including a surge tank handling liquid from and delivering it to the pump, an air tank, a connection between the tanks, and means acting to drain liquid from the air tank upon a predetermined quantity thereof accumulating therein, and a control for the first mentioned means including a pilot valve, a fluid connection between the pilot valve and jack controlled by the action of the jack and communicating pressure to the pilot valve to operate it, a fluid connection between the pilot valve and the inlet of the pump supplying fluid to the pilot valve to operate it when the first mentioned connection is not supplying pressure to operate the pilot valve, and means operating to make up escaping liquid.

11. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack and including a surge tank handling liquid from and delivering it to the pump, an air tank, a connection between the tanks, and means acting to drain liquid from the air tank upon a predetermined quantity thereof accumulating therein, and a control for the first mentioned means including a pilot valve, a fluid connection between the pilot valve and jack controlled by the action of the jack and communicating pressure to the pilot valve to operate it, a fluid connection between the pilot valve and the inlet of the pump supplying fluid

14

to the pilot valve to operate it when the first mentioned connection is not supplying pressure to operate the pilot valve, and means operating to add air to the accumulator, and means operating to make up escaping liquid.

12. In combination, a pump having an inlet and an outlet, a jack, a pressure accumulator, means connecting the pump, the accumulator and jack intermittently directing flow from the outlet of the pump to the jack and to the accumulator, the accumulator being in communication with the inlet of the pump when the outlet is delivering fluid to the jack, and a control for said means including a valve, a fluid connection between the valve and jack controlled by the action of the jack and communicating pressure to the valve to operate it, a fluid connection between the valve and the inlet of the pump supplying fluid to the valve to operate it when the first mentioned connection is not supplying pressure to operate the valve, means operating to add air to the accumulator, and means operating to make up escaping liquid.
15. In combination, a pump having an inlet and an outlet, a jack, a pressure accumulator, means connecting the pump, the jack and accumulator and jack intermittently directing flow from the outlet of the pump to the jack and to the accumulator, the accumulator being in communication with the inlet of the pump when the outlet is delivering fluid to the jack and including a valve, a fluid connection between the valve and the inlet of the pump supplying fluid to the valve to operate it when the first mentioned connection is not supplying pressure to operate the valve, means operating to add air to the accumulator, and means operating to make up escaping liquid.
16. In combination, a pump having an inlet and an outlet, a jack, a pressure accumulator, means connecting the pump and jack intermittently directing flow from the outlet of the pump to the jack and to the accumulator including a main valve alternately connecting the inlet of the pump with the jack and accumulator and alternately connecting the outlet of the pump with the jack and the accumulator, and a control for said means including a valve, a fluid connection between the valve and jack controlled by the action of the jack and communicating pressure to the valve to operate it, and a fluid connection between the valve and the inlet of the pump supplying fluid to the valve to operate it when the first mentioned connection is not supplying pressure to operate the valve.
